UNITED STATES PATENT OFFICE

RICHARD SCHEID, OF ST. LOUIS, MISSOURI

HEATER CONSERVER PLATE

Application filed February 27, 1928. Serial No. 257,362.

This invention relates to new and useful improvements in heater conserver plates of the type used on gas ranges and the like.

The principal objects of the invention are to provide a plate so constructed as to deflect flames and heat of a burner toward the open center of the plate and under the base of the utensil supported by said plate, thereby preventing the escape of the heat past the sides 10 of the utensil and concentrating the heat under the base thereof.

Further objects of the invention are to provide a heat conserver of the class described which is of durable construction and is arranged so as to support the utensil in spaced relation with the body of the plate, thereby facilitating the circulation of heat and flame under the base of the utensil, and which heat conserver can be manufactured at low cost.

Additional objects of the invention are to provide a heat conserver plate having a marginal inverted trough or pocket for trapping the flames and the heat and deflecting it centrally under the base of the utensil, the latter 25 being supported by suitable projections formed integral with the plate in spaced relation therewith. With these and other objects in view, my invention consists of certain novel features and arrangements of parts herein 30 after more fully described and claimed and illustrated in the accompanying drawings in which—

Figure 1 is a side elevation of the plate showing a utensil in dotted lines supported 35 thereon.

Figure 2 is an enlarged plan view of the heat conserver plate.

Figure 3 is a vertical cross section of the same.

Referring by numerals to the accompanying drawings, 10 indicates a plate having a central opening 11. The outer flange 12 of said plate is curved upwardly in cross section to provide an inverted annular pocket or 45 trough 14. The outer edge 15 of flange 12 is presented downwardly and terminates a suitable distance below the horizontal plane of the inwardly and horizontally disposed flange 16. The latter is formed integral with the 50 curved wall 18 of pocket 14 and the junction

of said flange 16 with said wall forms an ogee curve which thus provides an uninterrupted smooth surface between pocket 14 and the central opening 11. In this manner the passage of hot air and gasses from the pocket 14 inwardly toward the central opening 11 is facilitated and natural circulation is thereby provided so that very little heat escapes outwardly past the edge 15.

A series of inwardly presented fingers or projections 19 is formed integral with plate 10 and said fingers preferably project a suitable distance within opening 11 beyond the edge of flange 16. These fingers extend upwardly from the upper face of flange 16, their thickness being greater than the thickness of said flange so that the upper faces of said projections or fingers are disposed in a horizontal plane spaced a suitable distance above the horizontal plane of flange 16. Thus, when a utensil is supported by said projections or fingers, a clearance space is provided between flange 16 and the bottom of the base of said utensil, thereby enabling hot air and gases to pass outwardly along the bottom of the base and then upwardly past the edge of the base. In this manner heat and gases are induced to circulate from pocket 14 inwardly through the central opening 11 under the bottom of the utensil so that all of the heat generated by the burner is utilized.

The crown portion 12^a of flange 12 is preferably disposed above the horizontal plane of projections 19 so as to provide an annular raised wall which forms a shelter for the base of the utensil and prevents outside air currents from interfering with or checking the circulation of hot air and gases in close proximity to the utensil.

The heat conserver plate is preferably formed of a single piece of metal, preferably a casting, which enables the manufacture of plates at low cost and at the same time provides an article of the desired strength and durability necessary to support the utensil.

I claim:

1. A heat conserver plate comprising a single piece member having the marginal portion formed with a downwardly opening trough, the outer edge of which is presented

downwardly and the inner edge of which is curved inwardly and terminates in a horizontal plane to form a central opening, and projections formed integral with said plate and projecting radially inward within said opening, the upper faces of said projections being disposed in a plane above the top of said inward and horizontal edge.

2. A heat conserving plate comprising a single piece casting having the marginal portion formed with a downwardly opening annular pocket, the outer edge of said marginal portion being presented downwardly and the inner edge thereof being presented inwardly and terminating in a horizontal plane to form a central opening, said inner edge being disposed in a horizontal plane above the plane of said outer edge, and projections formed integral with said inner edge and projecting radially inward within said opening, the upper faces of said projections being disposed in a plane above the plane of said inner edge and below the top of said trough portion.

3. A heat conserving plate comprising a single piece casting having a central opening and an inverted marginal trough opening downwardly, the outer edge of said trough portion being presented downwardly and the inner edge of said trough portion being disposed horizontally to form said central opening, said inner edge being disposed in a plane above the plane of said outer edge and below the plane of the crown of said trough portion, and projections formed integral with said plate and projecting radially inward within said opening, the upper faces of said projections being disposed above the plane of said inner edge.

4. As a new article of manufacture, a heat conserving plate comprising a single piece casting having its outer portion formed with a marginal pocket opening downwardly, the central portion of said plate being formed perforate and provided with a series of integral projections projecting inwardly, said central portion being disposed on a horizontal plane above the plane of the outer edge of said marginal pocket and below the plane of said projections.

50 In testimony whereof I hereunto affix my signature this 23rd day of February 1928.

RICHARD SCHEID.
